CLAIM

The ornamental design for a package for cosmetic products, as shown and described.

DESCRIPTION

FIG. 1 is a perspective view of a package for cosmetic products showing the new design;

FIG. 2 is a front view thereof;

FIG. 3 is a back view thereof;

FIG. 4 is a left side view thereof, the right side view being a mirror image thereof;

FIG. 5 is a top view thereof; and,

FIG. 6 is a bottom thereof.

The broken lines in the figures depict portions of the package for cosmetic products that form no part of the claimed design.
